[57] CLAIM

The ornamental design for a bottle, substantially as shown and described.

DESCRIPTION

FIG. 1 is a front elevation view of a bottle showing our new design, the opposite side being a mirror image thereof;

FIG. 2 is a top plan view;

FIG. 3 is a bottom plan view;

FIG. 4 is a view looking from the left of FIG. 1;

FIG. 5 is a view looking from the right of FIG. 1;

FIG. 6 is a sectional view taken on lines 6—6 of FIG. 1; and

FIG. 7 is a fragmentary sectional view taken on the line 7—7 of FIG. 3.

FIG. 4.

FIG. 5.

FIG. 7.

FIG. 6.
